Specification of Letters Patent. Patented July 26, 1910.

Application filed January 24, 1910. Serial No. 539,739.

To all whom it may concern:

Be it known that I, MORITZ SCHRADER, a subject of the Czar of Russia, residing at McKeesport, in the county of Allegheny and State of Pennsylvania, have invented certain new and useful Improvements in Firearms, of which the following is a specification, reference being had therein to the accompanying drawing.

10 This invention relates to firearms, and more particularly to that class known as magazine or automatic pistols, wherein the barrel of the pistol is charged with cartridges from a magazine contained within 15 the handle of the pistol.

15 The primary object of my invention is to provide a pistol consisting of comparatively few parts, easily assembled, safely operated and easily maintained in an operable condition.

Another object of this invention is to provide a magazine pistol with a novel safety device adapted to prevent the pistol from being accidentally discharged.

25 A further object of the invention is to provide a pistol of the above type with a novel shell extractor adapted when moved in one direction to extract a shell and set the trigger and when released reload the barrel 30 with a cartridge.

With the above and such other objects in view as may hereinafter appear, the invention consists of the novel construction, combination and arrangement of parts to be 35 hereinafter specifically described and then claimed.

Reference will now be had to the drawings forming a part of this specification, wherein there is illustrated a preferred embodiment of the invention, but it is to be understood that the structural elements thereof can be varied or changed, as to the size, shape and manner of assemblage without departing from the spirit and scope of 45 the invention.

In the drawings:—Figure 1 is a side elevation of a pistol constructed in accordance with my invention, Fig. 2 is a similar view showing the side plate of the pistol removed, Fig. 3 is a plan of the pistol, Fig. 4 is a side elevation of the detached side plate, Fig. 5 is a vertical sectional view of the same, Fig. 6 is a view of one end of the

breech block, Fig. 7 is a side elevation thereof, Fig. 8 is a view of the opposite end of the breech block, Fig. 9 is an elevation of the opposite side of the breech block from that shown in Fig. 7, Fig. 10 is a vertical longitudinal sectional view of the breech block, Fig. 11 is a plan of the same, and Fig. 12 is a side elevation of a portion of the pistol body.

The pistol comprises a body made of light and durable metal, the body having the forward end thereof shaped to provide a barrel 1 and intermediate the forward end of the barrel 1 and the rear end of the body is a depending handle portion 2, which has the forward side thereof connected to the lower edge of the barrel 1 by a trigger guard 3. The body has formed therein a receiver 4 and the handle has a magazine chamber 5. The receiver 4 and the chamber 5 are closed by a side plate 6 secured to the body by screws 7 or other fastening means. The outer side of the plate 6 is provided with a handle plate 8 adapted to coöperate with a handle plate 9 carried by the outer side of the body to provide a hand grip for the handle portion 2 of the pistol.

80 The upper face of the barrel 1 is formed with a longitudinal rib 10 and the upper edge of this rib is in longitudinal alinement with the upper face of the pistol body, whereby the upper face of the body and rib can be provided with a longitudinal sight groove 11 adapted to extend from the rear end of the body to the forward end of the rib 10.

The bore 12 of the barrel 1 has the inner end thereof terminating at the forward end of the receiver 4, and the material bordering upon the lower edge of the rear end of the bore is cut away, as at 13 whereby a shell can be easily inserted in the rear end of the bore.

85 The inner and confronting sides of the pistol body and the side plate 6 forming the walls of the receiver 4 are provided with longitudinal grooves 14 and 15 and the forward end of the groove 14 is adapted to terminate in an extractor opening 16 formed in the body 1 at the rear end of the bore 12, the extractor opening 16 being of a sufficient size to allow a cartridge to pass there-through. The forward wall of this ex-

tractor opening is provided with a longitudinal slot 17 intersecting the wall of the bore 12, and the object of this slot will presently appear. The upper and lower edges 5 of the extractor opening 16 are beveled, as at 18 to permit of a shell easily passing through said opening.

Slidably mounted in the grooves 14 and 15 are the oppositely disposed longitudinal ribs 19 and 20 of a breech block 21. The rib 20 is provided with a longitudinal groove 22 extending from end to end of the rib and pivotally mounted in this groove by a transverse pin 23 is an extractor arm 24 having 15 the forward end thereof provided with a hook 25 and, at the rear end thereof engaged by a coil spring 26 located in a spring seat 27 provided therefor at the rear end of the rib 20. The breech block is provided with 20 two longitudinal bores 28 and 29, one arranged above the other, both bores having the rear ends thereof open, and the forward end of the bore 28 is reduced and the walls thereof threaded, as at 30 and the forward 25 end of the bore 29 is reduced to provide a firing pin opening 31.

Extending into the bore 28 of the breech block is a stem 32, extending through an opening 33 provided therefor in the rear 30 wall of the breech block 4. The outer end of the stem is provided with a knurled head 34 and the forward end of the stem is threaded, as at 35 and screwed into the reduced end 30 of the bore 28. The stem 35 adjacent to the threads 35 is provided with a collar 36 and encircling said stem between the collar 36 and the inner side of the rear wall of the receiver 4 is a coiled compression spring 37. This spring serves 40 to hold the forward end of the breech block against the forward wall of the receiver 4 and at the inner end of the bore 12.

The bottom of the breech block 21 is provided with a longitudinal slot 38 communicating with the bore 29. Slidably mounted in the bore 29 is a firing pin 39 having the forward end 40 thereof reduced and extending through the firing pin opening 31. The firing pin 39 is provided with a depending rib 41 adapted to extend into the slot 38 and prevent the firing pin from rotating in the bore 29. The lower edge of the rib 41 at the rear end thereof is provided with a depending lug 42 having a notch 43 formed 55 therein, the object of which will presently appear. The firing pin 39 is provided with a longitudinal socket 44 and arranged in said socket is a coiled spring 45. The spring 45 encircles a rod 46 having the rear end 60 thereof threaded or otherwise fixed, as at 47 in the rear wall of the receiver 4. The coiled spring 45 extends from the rear wall of the receiver 4 to the forward end of the socket 44 and is adapted 65 to normally retain the firing pin 39 in the

forward end of the bore 29. The rod 46 is of a sufficient length to extend into the socket 44 and prevent the coil spring 45 from buckling or becoming displaced when the breech block 21 is shifted.

The side walls of the receiver 4 below the grooves 14 and 15 are provided with longitudinal grooves 48, the forward ends of the grooves terminating at a trigger opening 49 formed in the forward wall of the receiver 70 4 and at the upper end of the magazine chamber 5, the opening 49 being opposite the forward part of the trigger guard 3. In the grooves 48 is slidably mounted a trigger yoke 50 having the forward end 80 thereof connected to a trigger 51 movably mounted in the opening 49. The forward edge of the trigger 51 is recessed, as at 52 to provide a finger grip. The rear end of the trigger yoke 50 is provided with a depending lug 53 and is also bifurcated to receive a roller 54. The roller 54 is adapted to engage the beveled end 55 of a sear 56, pivotally connected to the wall of the receiver 4 by a screw 57. The beveled end 55 90 of the sear 56 is normally held in engagement with the roller 54 by a flat spring 58 engaging the sear at its rear end, said spring being held by the bottom wall of the receiver 4.

The under face of the sear 56 is provided with a curved spring 59 and this spring is adapted to form part of a safety device carried by the side plate 6. The safety device comprises a pin 60 revolvable in the side 95 plate 6, the outer end of the pin having a crank 61 with one end thereof knurled, as at 62, whereby it can be easily gripped by the finger to rotate the pin 60. The inner end of the pin is provided with a dog 63 100 adapted to engage the end of the sear 56 between the springs 58 and 59 and lock the sear 56, whereby it cannot be actuated by a movement of the trigger yoke 50. When the dog 63 is swung downwardly past the spring 110 59, said spring is adapted to hold the dog 63 in an inactive position while the sear is being actuated by the yoke 50.

The magazine chamber 5 is provided with a vertical partition 64 parallel and in proximity to one of the walls of said chamber. This partition is engaged at the upper end thereof by the depending lug 53 of the trigger yoke 50 and thereby limits the outward movement of said yoke and the trigger 51. 115 Between the partition 64 and the wall of the chamber 5 is a flat spring 65 serving a two-fold purpose. The upper end of the spring extends behind the lug 53 and normally holds said lug in engagement with the partition 64, while the lower end of the spring 65 engages a magazine latch 66 pivotally mounted between the partition 64 and the wall of the chamber 5 by a pin 67. The lower end of the latch 66 is provided 120

a head 68 adapted to engage the lower end of a magazine 69 mounted in the chamber 5 between the partition 64 and the forward wall of said chamber, the bottom of said chamber being open to receive the magazine. The magazine 69 is of a conventional form containing a spring adapted to feed cartridges to the upper end of the magazine, and this magazine is adapted to extend 10 through the trigger yoke 50 and support a cartridge against the under side of the breech block 21.

To place a cartridge in the rear end of the bore 12 the handle portion 2 of the revolver is held in one hand and the stem 32 pulled outwardly to move the breech block 21 toward the rear wall of the receiver 4. As the breech block is carried rearwardly, the lug 42 of the firing pin 39 moves over 20 the upper edge of the sear 56 until said sear engages in the notch 43. During this movement of the breech block 21 the springs 37 and 45 are placed under tension, and as soon as the breech block clears the upper 25 end of the magazine 69, a cartridge is forced upwardly between the rear end of the bore 12 and the forward end of the breech block. As the cartridge is carried upwardly the rim thereof extends under the hook 25 of 30 the extractor arm 24, and the nose of the cartridge is pointed toward the bore 12, whereby when the stem 32 is released the tension of the spring 37 will restore the breech block 21 to its normal position, causing 35 the forward end of said member to push the cartridge into the rear end of the bore 12. The firing pin 39 is still held by the sear 56 with the spring 45 under tension. When the cartridge is forced into the bore 40 12 the slot 17 provides clearance for the hook shaped end 25 of the extractor arm 24, the hook remaining in engagement with the cartridge from the time it leaves the magazine until it has been fired and extracted from the revolver.

If it is desired to carry the revolver with a cartridge in the barrel and the firing pin and trigger ready for use, the safety device on the side plate 6 can be set to lock the sear 56 and thus prevent accidental discharge of the weapon. The safety device can be easily shifted with the thumb while the hand is gripping the handle portion 2 of the revolver and almost simultaneously with the 55 shifting of the safety device the trigger 51 can be pulled to shift the sear 56 and release the firing pin 39. The reduced end 40 of the firing pin can be arranged relatively to the body of the firing pin, whereby either 60 center or rim firing cartridges can be used.

After a cartridge has been fired, the pressure of the gases drives the breech block rearwardly, and the shell is withdrawn from the bore through the medium of the hook 65 25 of the extractor arm 24. After the breech

block has moved sufficiently to place the shell opposite the extractor opening 16, the rear end of the extractor arm 24 is pressed inwardly by contacting with the face of the groove 14, whereby the hook will be moved 70 out of engagement with the rim of the shell and to allow the next cartridge coming from the magazine to force the shell from the opening 16.

Having now described my invention what 75 I claim as new, is:

1. In a firearm of the type described, a body having a receiver therein and a barrel communicating with said receiver, a magazine adapted to extend into said receiver 80 to position cartridges to enter said barrel, a longitudinally-movable spring-pressed breech block in said receiver and comprising a body provided with superposed longitudinally-extending bores, a stem mounted in 85 the upper of said bores and fixedly connected at its forward end to the breech block with its rear end extending through the rear end of the body and provided with a head, a coil spring surrounding said stem 90 and confined thereon between the rear wall of the receiver and the fixed end of the stem, a firing pin mounted in the lower bore of the breech block and provided with a longitudinally-extending bore, a rod in said bore, 95 a coil spring surrounding said rod and confined between the end of the bore in the firing pin and the rear wall of the receiver, a rib carried by said firing pin and extending into a slot provided therefor in the lower 100 face of the breech block, said rib having a notch on the lower face thereof near its rear end, a spring-pressed sear pivotally-mounted in the receiver for engagement with said notch, a trigger, and a yoke carried by said 105 trigger for engagement with the sear to disengage the latter from said notch.

2. In a firearm of the type described, a body having a receiver therein, and a barrel communicating with said receiver for positioning cartridges to enter said barrel, a breech block longitudinally movable in said receiver and provided with superposed longitudinally-extending bores, a stem in the 110 upper of said bores having its forward end fixedly connected to the breech block and its rear end extending through the rear wall of the body, a coil spring on said stem confined between the face end of the stem and the rear wall of the receiver, a firing pin in the lower of said bores in the breech block and having a depending rib extending into a slot provided therefor in the lower face of the breech block, said rib provided at its 115 rear end with a notch, the said firing pin provided with a bore, a coil spring in said bore and confined therein between the closed forward end of the bore and the rear 120 wall of the receiver, a spring-pressed sear 125 130

5 pivotally-mounted in the receiver for engagement with the notch in said firing pin rib, a trigger, mechanism carried by said trigger for engagement with the sear to release the latter from its engagement with the 10 firing pin rib, and means for limiting the forward movement of said sear releasing mechanism.

3. In a firearm of the type described, a body having a receiver therein, and a barrel communicating with said receiver, a magazine extending into said receiver for positioning cartridges to enter said barrel, a breech block longitudinally movable in said receiver and provided with superposed longitudinally-extending bores, a stem in the upper of said bores having its forward end fixedly connected to the breech block and its rear end extending through the rear wall 15 of the body, a coil spring on said stem confined between the face end of the stem and the rear wall of the receiver, a firing pin in

the lower of said bores in the breech block and having a depending rib extending into a slot provided therefor in the lower face of the breech block, said rib provided at its rear end with a notch, the said firing pin provided with a bore, a coil spring in said bore and confined therein between the closed forward end of the bore and the rear wall 20 of the receiver, a spring-pressed sear pivotally-mounted in the receiver for engagement with the notch in said firing pin rib, a trigger, mechanism carried by said trigger for engagement with the sear to release the latter from its engagement with the firing 25 pin rib.

In testimony whereof I affix my signature in the presence of two witnesses.

MORITZ SCHIRADER.
